UNITED STATES PATENT OFFICE.

GEORGE H. TABER, JR., OF RYE, NEW YORK, ASSIGNOR TO SINCLAIR REFINING COMPANY, OF NEW YORK, N. Y., A CORPORATION OF MAINE.

ART OF CRACKING HYDROCARBONS.

Application filed November 26, 1927. Serial No. 235,860.

This invention relates more particularly to improvements in cracking operations carried out to produce lighter and lower boiling hydrocarbon oils, such as gasoline, from 5 heavier and higher boiling hydrocarbon oils, such as kerosene, gas oil, fuel oil and the like. The invention is of special value in connection with distillation operations carried out under superatmospheric pressure, 10 but it is also useful in connection with other types of operations, such as those in which the oil to be cracked is heated to a cracking temperature in the vapor-phase either at approximately atmospheric pressure or at 15 higher pressures and those in which the oil is heated to a cracking temperature, usually under very high pressures, without complete separation of vapors and unvaporized liquids in the cracking operation itself.

20. In cracking operations in which the cracked products are taken off as a mixture of vapors and gases, either from the cracking operation itself or from some subsequent operation carried out to separate the lighter 25 cracked products from residues the constituents of which are unsuitable as components of the desired product, the gas-vapor mixture usually includes gases incondensable except under high pressures and at low tem- 30 peratures as well as vapors of the desired lighter lower boiling hydrocarbon oils. In the usual condensing operation, a certain amount of the constituents suitable as components of the desired product are carried off uncondensed with such incondensable 35 gases. The recovery of condensable constituents suitable as components of the desired product escaping with the gas-vapor mixture remaining uncondensed from the condensing 40 operation is of course desirable to improve the yield secured from the cracking operation. This invention provides an improved method of recovering such condensable constituents from such gas-vapor mixtures.

45. According to the present invention, the gas-vapor mixture from the cracking operation is subjected to a fractionating operation, the gas-vapor mixture remaining from the fractionating operation is subjected to a 50 condensing operation, the gas-vapor mixture remaining uncondensed from the condensing operation is subjected to a scrubbing treatment with a higher boiling oil fraction from the fractionating operation, and 55 the oil containing constituents absorbed from

the gas-vapor mixture in the scrubbing operation is reintroduced into the fractionating operation. The relatively low boiling condensable constituents separated in the scrubbing operation from the gas-vapor mixture remaining uncondensed from the condensing operation are thus condensed together with a relatively large proportion of higher boiling constituents to form a stable condensate while the heat of the gas-vapor mixture from the cracking operation given up in the fractionating operation is utilized to effect stripping of the absorbed constituents from the scrubbing oil. The higher boiling oil containing absorbed constituents 60 from the scrubbing operation may with advantage be preheated, for example, by heat exchange with the gas-vapor mixture escaping from the fractionating operation, before reintroduction into the fractionating 65 operation. To assist in the recovery of low boiling condensable constituents, the condensing operation and the fractionating operation may be carried out under pressure 70 substantially above atmospheric pressure. 75

The invention will be further described in connection with the accompanying drawings, which diagrammatically illustrate one form of apparatus adapted for carrying out the process of the invention. Fig. 1 illustrates a form of apparatus for carrying out 80 the invention in conjunction with various types of cracking operations, and Fig. 2 illustrates this form of apparatus as embodied in a system for carrying out one 85 type of cracking operation. It will be appreciated that different types of apparatus may be employed to carry out the various steps effected in the apparatus shown, that the process of the invention is useful in connection with types of cracking operation other than that particularly illustrated, and that a recovery system such as that illustrated 90 may be employed in connection with one or several cracking units. 95

100 Referring more particularly to Fig. 1, the gas-vapor mixture from the cracking operation enters fractionating tower 3 through connection 4. The gas-vapor mixture remaining from the fractionating operation 105 escapes through connections 5 and 6 to condenser 7, passing on the way through heat exchanger 8. Condenser 7 discharges through connection 9 into receiving tank 10. From tank 10, the condensate is discharged

either through connection 11 or through connection 12 after passing through separating tank 13. The uncondensed gas-vapor mixture from receiving tank 10, together with any uncondensed vapors and gases separated in tank 13, escapes to scrubbing tower 15 through connection 14. Other hydrocarbon gas-vapor mixtures containing condensable constituents of corresponding character may 5 also be supplied to scrubbing tower 15 through connection 16 by means of compressor or blower 17. Part of the higher boiling oil collecting in the lower end of fractionating tower 3 is circulated through cooler 18 and then introduced into scrubbing tower 15 through connection 19 by means of pump 20. The scrubbing oil containing absorbed constituents from scrubbing tower 15 is reintroduced into the fractionating tower 3 10 through connection 21 or connection 22 or both of these connections by means of pump 23 after passing through heat exchanger 8. The gas or gas-vapor-mixture remaining from the scrubbing operation escapes through connection 24. The condensable constituents absorbed in the scrubbing oil in the scrubbing tower 15 are stripped from this oil in the fractionating tower 3 to be condensed in condenser 7 together with the major part 15 of the condensable constituents of the gas-vapor mixture from the fractionating operation. Part of the higher boiling oil collecting in the lower end of fractionating tower 3 may be discharged through connection 25 and cooler 26. An intermediate cut may also be discharged from the fractionating tower through connection 27 and cooler 28.

The fractionating tower 3 may be cooled by exposure, or partial exposure, to the atmosphere, or by circulating a suitable cooling medium in indirect heat exchanging relation with the gas-vapor mixture in the upper end thereof, or by the direct introduction into the upper end thereof of part 40 of the distillate product or a fraction of corresponding character, or by the direct introduction of higher boiling oil which then escapes with higher boiling fractions separated in the tower. Part of the cooling required, in 45 some cases even all of it, is supplied by the introduction of the charged scrubbing oil from the scrubbing operation. Except where atmospheric cooling is relied upon, it is usually advantageous to lag or thermally insulate fractionating tower 3.

Although cooler 18 may in some cases be dispensed with, the absorbent capacity of the scrubbing oil is increased by cooling it as it circulates from the fractionating operation to the scrubbing operation. In the process of the invention, it is particularly advantageous to preheat the charged scrubbing oil from the scrubbing operation before reintroduction into the fractionating operation. This preheating is with advantage

effected by heat exchange with the gas-vapor mixture from the fractionating operation, as in heat exchanger 8. As the degree of pre-heating increases, with a fractionating tower such as that illustrated, the charged scrubbing oil may be introduced at a lower point or the proportion of the charged scrubbing oil introduced at the lower of two or more points may be increased. 70

While the fractionating operation and the 75 subsequent condensing operation may be carried out under approximately atmospheric pressure, substantially higher pressures may be maintained on these operations to assist in the recovery of low boiling condensable constituents. In conjunction with pressure distillation cracking operations, for example, substantially the still pressure may be maintained through fractionating tower 3 and condenser 7, or the fractionating tower and condenser may be operated under an intermediate pressure above atmospheric. Likewise, the fractionating tower may be operated under a pressure higher than that maintained in the condenser. Where condenser 80 7, in the apparatus illustrated, is operated under approximately atmospheric pressure, separating tank 13 may be dispensed with; its use is not essential in any case. Where condenser 70 is operated under a pressure 85 substantially higher than atmospheric, however, it is advantageous to maintain receiving tank 10 under substantially the same pressure maintained in condenser 7 and to reduce the pressure on the condensate approximately to atmospheric as it is discharged into a separating tank 13 as shown. 90

The scrubbing operation may be carried out under atmospheric pressure or under a slightly higher pressure, for example, sufficient to force the stripped gas from the scrubbing operation to storage or to burners or to other point of disposition. 105

The system illustrated in Fig. 2 comprises a pressure still of the general type described 110 and illustrated in Letters Patent No. 1,285,200 granted November 19, 1918, to the Sinclair Refining Co. on the application of Edward W. Isom. The still comprises a bulk supply drum located away from a battery of vertical tubes in a heating furnace and connections including a circulating pump for circulating oil from the bulk supply drum upwardly through the heating tubes and back to the bulk supply drum. 115 Vapors and gases escape from the bulk supply drum to a reflux tower 29 from which the gas-vapor mixture remaining uncondensed escapes through connections 30, 31 and 4' to the apparatus for carrying out the 120 present invention. The same parts illustrated in Fig. 1 and described in connection therewith are in Fig. 2 designated by the same reference character with a prime appended. 125 130

The operation of scrubbing tower 3', heat exchanger 8', condenser 7', receiving tank 10', separating tank 13', cooler 18', and scrubbing tower 15', are the same as has been 5 described in connection with the apparatus illustrated in Fig. 1. For cooling fractionating tower 3', a part of the distillate product discharged from receiving tank 13' is returned through connection 32 by means of 10 pump 33 and reintroduced into the upper end of the fractionating tower, the rate at which this distillate is so reintroduced being regulated to maintain the temperature at which the gas-vapor mixture escapes from 15 the fractionating tower at the desired value. The condensate discharged from receiving tank 10' may be discharged to separating tank 13' either directly through connection 34 or through cooler 35. Connection 36 is 20 provided for introducing any gases and vapors from the separating tank 13' into the scrubbing tower 15' through connection 16' by means of blower or compressor 17', for example, where the scrubbing tower is 25 operated under a pressure higher than that prevailing in the separating tank.

Connection 37 is provided for discharging stripped gases from the scrubbing tower 15' to a gas holder and connection 38 is provided 30 for discharging these gases, for example, to burners for supplying heat to the cracking operation. Traps for the separation of any liquid from the gas mixture passing through the associated connections are shown at 39 and 40.

In addition to the gas-vapor mixture from the cracking operation introduced into scrubbing tower 15' through connection 14', other refinery gases may be introduced into the scrubbing tower, for example, through connection 41, and similarly gases produced during distillation of tars or residues from cracking operations may also be introduced into the scrubbing tower, through connection 45 42 in the apparatus illustrated in Fig. 2.

The apparatus for distilling tar discharged during operation of the pressure cracking still illustrated in Fig. 2 comprises an evaporating tower 43 and a fractionating tower 44. Tar discharged from the pressure cracking still is introduced while hot into the lower end of tower 43 through connection 45, a pressure being maintained in tower 43 substantially lower than that prevailing 50 in the pressure cracking still so that the lower boiling components of the tar are distilled by the self-contained heat of the tar on reduction in pressure. The residue from tower 43 is discharged through cooler 46. 55 Connection 47 is provided for introducing a low boiling oil into tower 44 to control the fractionating operation therein. Low boiling oils escape from

tower 44 as vapors to condenser 50 and higher boiling oils condensed in the tower are discharged through cooler 51. Any gas or gas-vapor mixture separating from the distillates discharged from condenser 50 and 70 cooler 51 escape through connection 42.

In the operation of the pressure cracking still illustrated, raw oil is introduced into the upper end of the reflux tower through connection 52, there assisting in effecting and 75 controlling the refluxing operation, and through the bearings of the circulating pump 53 through connection 54, there assisting in cooling and lubricating the pump bearings. Pump 55 is provided for charging 80 the still through connection 56 at the beginning of a run. At the end of a run the charge remaining in the still is pumped out through connection 56 and cooler 57 by means of pump 58. Where the tar from a 85 number of cracking operations is discharged into tower 43, the tar so pumped out of the still at the end of a run may be introduced into tower 43 through connection 59 there to be distilled.

Condenser 60 and connections 61 and 62, normally closed, are provided for emergency use. Similarly, by-pass connections 63, 64, 65 and 66, normally closed, are provided for use as occasion requires. Connections 12', 95 67, 68, 41, 69, 70, 71, 72, 73, 74, 75, and 76 lead to storage tanks of suitable capacity to permit continued operation, in commercial practice, and to provide adequate flexibility of operation. Usually but one system 100 of tankage is required for a number of cracking units.

The operation of the fractionating towers 3' and 44, in the apparatus illustrated in Fig. 2, may be controlled so that the higher 105 boiling fractions separated therein and discharged through connections 77 and 78 are available as charging stock again to be introduced into the pressure cracking still. Connections 79 and 80 are provided for this 110 purpose. To improve heat economy in such operation by-pass 81 is provided around cooler 26' to permit the return of this fraction, or as much of it as can be so returned without excessively increasing the temperature of the oil entering the pressure cracking still, in a heated state. A by-pass around cooler 51 may be similarly arranged and 115 operated.

In operation to produce gasoline from gas oil in apparatus such as illustrated in Fig. 2, for example, the pressure cracking still may be operated under a pressure in the neighborhood of 125-150 lbs. per sq. in. and at a corresponding cracking temperature. 125 This pressure may be maintained through the reflux tower 29 and reduced approximately to atmospheric pressure or to an intermediate pressure by means of valve 82, or the still pressure may be maintained 130

through the fractionating tower 3', the condenser 7', and the receiver 10'. Similarly, the pressure may be initially or further reduced by means of valve 83 between the 5 fractionating tower 3', and the condenser 7' operated at approximately atmospheric pressure or at some higher intermediate pressure. The scrubbing tower 15' may be operated under approximately atmospheric 10 pressure or under a higher pressure; this pressure may be the same as that prevailing in the separating tank 13' or higher. Any pressure reduction between the receiving tank 10' and the scrubbing tower 15' may be 15 regulated by means of valve 84, and the pressure in the scrubbing tower 15' may be regulated by means of valve 85. The gasoline, or gasoline-containing pressure distillate produced in the operation is discharged 20 through connection 12' or, if separating tank 13' is not used, through connection 11'. A kerosene or furnace oil cut may be discharged through connection 72. The operation of fractionating tower 44 may be controlled 25 so that the condensate discharged through connection 74 corresponds in character to that discharged through connection 12', or so that it includes in addition higher boiling components corresponding to 30 the fraction discharged through connection 72. Residual fuel oil is discharged through connection 76. Gas oil character fractions may be discharged through connections 73 and 75 or either of them.

35 While the invention is of special value and application as an operation combined with cracking operations, in certain aspects it includes more general applications. The invention is useful in the recovery of gasoline components from a wide variety of 40 hydrocarbon gas and gas-vapor mixtures. The combined scrubbing operation and fractionating operation may also be carried out in conjunction with fractionating operations 45 applied to the separation of gasoline components and higher boiling oils other than those directly associated with cracking operations with certain advantages of the invention.

50 I claim:

1. An improvement in cracking hydrocarbon oils which comprises subjecting the gas-vapor mixture from the cracking operation to a fractionating operation and then subjecting the remaining gas-vapor mixture 55 to a condensing operation, subjecting the gas-vapor mixture remaining uncondensed from the condensing operation to scrubbing treatment with a higher boiling oil fraction from the fractionating operation, preheating the oil containing constituents 60 absorbed from the gas-vapor mixture in the scrubbing operation into the fractionating operation.

2. An improvement in cracking hydrocarbon oils which comprises subjecting the gas-vapor mixture from the cracking operation to a fractionating operation and then subjecting the remaining gas-vapor mixture to a condensing operation, subjecting the 65 gas-vapor mixture remaining uncondensed from the condensing operation to scrubbing treatment with a higher boiling oil fraction from the fractionating operation, preheating the oil containing constituents absorbed 70 from the gas-vapor mixture in the scrubbing operation and then reintroducing the preheated oil into the fractionating operation.

3. An improvement in cracking hydrocarbon oils which comprises subjecting the 80 gas-vapor mixture from the cracking operation to a fractionating operation and then subjecting the remaining gas-vapor mixture to a condensing operation, this fractionating operation and this condensing operation being carried out under superatmospheric pressure, subjecting the gas-vapor mixture remaining uncondensed from the condensing operation to scrubbing treatment with a higher boiling oil fraction from the fractionating operation, and reintroducing the 85 oil containing constituents absorbed from the gas-vapor mixture in the scrubbing operation into the fractionating operation.

4. An improvement in the recovery of 95 condensable gasoline components from gas mixtures containing the same, which comprises subjecting a gasoline-including vapor mixture to a fractionating operation and condensing components higher boiling than 100 gasoline therein, subjecting the remaining vapor mixture to a condensing operation and condensing gasoline therein, subjecting the gasoline-including gas mixture to scrubbing treatment with higher boiling oil from 105 the fractionating operation and reintroducing oil containing absorbed gasoline components from the scrubbing operation into the fractionating operation, whereby the 110 gasoline components absorbed from the gas mixture are condensed together with the gasoline components from the first mentioned vapor mixture in the said condensing operation and whereby the heat of the gasoline-including vapor mixture subjected to 115 the fractionating operation is utilized to strip absorbed gasoline components from the scrubbing oil.

In testimony whereof, I have subscribed my name.

GEORGE H. TABER, JR.
